UNITED STATES PATENT OFFICE.

JENS JOHAN MICHAEL LANGE, OF SVENDBORG, DENMARK.

FIRE-BOX FOR FIREPLACES.

SPECIFICATION forming part of Letters Patent No. 735,532, dated August 4, 1903.

Application filed September 12, 1902. Serial No. 123,092. (No model.)

To all whom it may concern:

Be it known that I, JENS JOHAN MICHAEL LANGE, engineer, of Svendborg, in the Kingdom of Denmark, have invented an Improvement in Fire-Boxes for Fireplaces, of which the following is a specification.

The well-known types of slow-combustion stoves in which the combustion takes place from above downward have the advantage of consuming coal which easily cakes together. On the other hand, they have the drawback that the stove when the fire has burned down low must be cleared out and then refilled and ignited, which causes not only a loss of time, but also a very undesirable development of smoke. Other types of slow-combustion stoves in which the combustion takes place from the bottom upward suffer from the drawback that in these stoves anthracite only can be used.

The present invention relates to a fireplace for open chimneys, stoves, furnaces, and the like, and is designed to retain the advantages of the above-mentioned types, while at the same time avoiding their drawbacks. This result is obtained by the fact that the improved fireplace, in which the combustion takes place from above downward, comprises a container for holding the fuel, having openings for the introduction thereof and for the passage of air, and in which container the remaining glowing embers of the fuel can by means of a turning movement be pushed upward and spread out over the fresh fuel.

The invention is illustrated in the accompanying drawings, showing various constructional forms of the fireplace.

Figures 1 and 2 represent vertical sections through a fireplace adapted according to the present invention. Fig. 3 is a front elevation thereof. Figs. 4 and 5 are details. Figs. 6 and 7 represent two modifications.

In the constructional form shown in Figs. 1 to 5, *a* is the stove-drum, having in front a large opening *b*, and above this one a guard *c*. Inside the drum *a* is arranged a cylindrically-curved draft-grate *f*, provided with openings *e*, and which extends upward in front of the lower part of the opening *b*. Above the grate *d* and inside the mantel *a* is arranged a hollow cylinder *g*, serving as the fire-chamber and mounted turnably upon two pivots *h*. The cylinder-wall is at two places *i k* oppo-

site to one another open almost for the whole length of the cylinder and for a width corresponding approximately to that of the grate *d*. The mantel of the cylinder consists partly of a plate *n*, lined with fireproof material *m*, and partly of a grate *p*, with openings *q*, corresponding to the openings *e* in the draft-grate *f*. Along the edges of the plates *n* and *p* are arranged a number of projections *r s*, respectively, shaped as fingers, teeth, or the like, or in connection with one another, so as to form a projecting edge, rail, or flange. 65

Above the cylinder *g* is arranged a cylindrically-curved cover *u*, capable of turning on a bolt *t*, and which can be shut down over the cylinder *g*. When this cover is lifted, there will be free access to the interior of the cylinder *g*, provided that the latter is turned so that one of the openings *i* or *k* is in proper position at the time. The cover *u* can be turned by means of an arm *v* and a rod *w* and is provided with a plate *x*, which when the cover is lifted is turned downward against a fixed stop *y* inside the mantel. (Vide Fig. 2.) 75

The plate *x* is by means of a hinge connected with a plate *z*, that rests upon one or more rollers *l*, and which is pushed up or down simultaneously with the plate *x* in opposite direction to the movements of the cover *u*. When the latter is completely shut, the upper edge of the plate *z* reaches almost up to the mantel or to a fixed rail or flange *2*, secured to the mantel. There will, however, always be a narrow slit left between the rail *2* and the edge of the plate *z*, through which the smoke passing along the outside of the plate *z* may be drawn away. 90

The rotary movement may, by way of example be imparted to the cylinder *g* by means of a turnable lever *4*, carrying a pawl *3*, that gears with the teeth of a tooth-wheel *5*, mounted upon one of the pivots *h*. 95

The fireplace acts in the following manner: During combustion the cylinder is made to assume the position shown in Fig. 1 when the aperture *i* of the cylinder is just above the grate *d*, which then forms the bottom of the fire-chamber. If fresh fuel is to be introduced, the cylinder *g* is by means of the rod *4* turned in the direction indicated by the arrow *6* until the aperture *i* comes up below the cover *u*. The grate *p* will during this turning partly push itself below the glowing em-

bers resting upon the grate *d* and partly carry them along until they have been raised to a certain height, when they will drop down again upon the grate *d*. This latter will when the cylinder has been turned about one hundred and eighty degrees again form the bottom of the fire-chamber, the aperture *k* being then above the grate *d*. (See Fig. 2.) The fresh fuel is then introduced and the cover *u* closed, whereupon the cylinder *g* is again turned about one hundred and eighty degrees by means of the rod 4. During this turning of the cylinder its contents will also be carried around, as the unevennesses of the cylinder, the edge of the plate *n*, with lining *m*, and the projections *r's* will serve as carriers for the fuel. A turning of about one hundred and eighty degrees will thus turn the contents of the cylinder upside down, so that the glowing embers are now on top of the fresh fuel. During the introduction of the fresh fuel the momentaneously-developed smoke will pass to the chimney between the edge of the cover *u* and the guard *c*, the cover *u* being opened and the plate *x* being simultaneously lowered to the position shown in Fig. 2. When the cover *u* is shut, the plate *x* will be raised, and the smoke can now pass out through the opening 7 between the plate *x* and the stop *y*. When the cover *u* is but partly open, the plate *x* but partly closes the opening 7, and it will consequently be possible to regulate the draft simply by opening the cover *u* more or less. If it be desired to obtain a brisk draft, the cylinder may be turned from the position shown in Fig. 1 in the direction opposite to that indicated by the arrow 6, so that the aperture *i* comes in front of the grate *f* and that the grate *d* is closed by the plate *n*. The air will then pass in through the holes *e* of the grate *f*, and, owing to the increased draft thus produced, the ignition of the fuel will rapidly increase in intensity. In order to effect a turning of the cylinder in the direction opposite to that of the arrow 6, the arm 4 is provided with a pawl 8, which by means of a rod 9 and a handle 10 can be made to gear with a tooth-wheel 11, mounted alongside the tooth-wheel 5, the pawl 3 being simultaneously brought out of gear.

As it may happen during the turning of the cylinder that pieces of fuel may drop out through the holes *q* and be squeezed in between the grates *f* and *p*, whereby the turning of the cylinder will be rendered difficult, the grates *d* and *f*, which are in rigid connection with each other, are mounted in a movable manner. To this end the connected grates *d* and *f* besides resting upon the fixed bolt 12 are further supported by a pin 13, capable of moving in a slot in the side plate of the stove, and which is secured to a lever 15, that carries a counterweight 16 and turns on a pin 14 on the side plate.

65 By turning the cylinder *g* very little to the one or the other side the holes *e* and *q* may be caused to be covered partly by the plates

p f, and in this way the draft through the draft-grate may be regulated as desired.

In the constructional form of the invention shown in Fig. 6 the grate *d* and the cover *u* are mounted movably in grooves in the end walls of the cylinder. By suitably moving the grate *d* or the cover *u* the draft through the grate *p* or the outlet to the chimney may be regulated. In other respects the fireplace acts in the same manner as that shown in Figs. 1 to 5.

In the constructional form shown in Fig. 7 the cylinder *g* is a fixture and is provided at the bottom with a grate 18 and at the top with a feeding-opening *k*, which can be closed by the cover *u*. Inside the cylinder is arranged a wing 19, which can be turned by a suitable handle from the outside.

When it is desired to introduce fresh fuel, the wing 19 has to be turned in the direction indicated by the arrow 20. The wing will then push the glowing embers away from the grate 18 and carry them upward until the wing is stopped, which takes place shortly before it reaches the position shown in Fig. 7. The fresh fuel is now thrown in, whereupon the wing is turned farther in the direction indicated by the arrow 20. Owing to this turning the glowing embers resting upon the wing will slide down and be spread over the fresh fuel.

In lieu of the container being made of a cylindrical form it may be made prismatical or spherical.

Having now particularly described and ascertained the nature of my said invention and in what manner the same is to be performed, I declare that what I claim is—

1. A fireplace of the kind described, comprising a container for fuel, consisting of a horizontally-mounted rotating cylinder having two large openings and draft-openings between the first-named openings, projections in the cylinder operating to cause the fuel to partake of a rotary movement with the cylinder, and a swinging cover for one of said large openings, substantially as specified.

2. In a fireplace, or the like, a cylindrical rotary fuel-holder having opposite openings and draft-openings, a fixed grate below the holder and a prolongation for said grate, and having openings for regulating said draft-openings, substantially as specified.

3. In a fireplace, or the like, a rotary fuel-holder having inwardly-projecting teeth, the said holder also having opposite openings, a swinging cover for one of the openings, a deflecting-plate pivoted to said cover, and rollers on which said plate moves, substantially as specified.

In testimony whereof I have signed my name to this specification in the presence of two subscribing witnesses.

JENS JOHAN MICHAEL LANGE.
